UNITED STATES PATENT OFFICE.

KARL ALBERT FREDRIK HIORTH, OF CHRISTIANIA, NORWAY.

ELECTRIC INDUCTION SMELTING-FURNACE.

980,259.

Specification of Letters Patent.

Patented Jan. 3, 1911.

Application filed May 18, 1910. Serial No. 562,045.

To all whom it may concern:

Be it known that I, KARL ALBERT FREDRIK HIORTH, a subject of the King of Norway, residing at Christiania, Norway, have invented certain new and useful Improvements in Electric Induction Smelting-Furnaces; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In electric induction smelting furnaces, in which the primary winding is located between the furnace groove and the magnet core, it is impossible to use large charges, because the stray loss becomes great when the diameter of the furnace and thereby the space between the furnace groove and the magnet core is increased. According to the present invention this is avoided by making the magnet core or part of it hollow and consequently enabling it to be formed with so large diameter, that it will be comparatively near to the furnace groove.

The invention is illustrated in the accompanying drawing, in which the figure is a diagrammatic longitudinal vertical section of a furnace embodying my invention.

1 indicates the furnace groove, 2 the portion of the magnet core located within said groove 1, which portion in the drawing has the form of a drum or a cylinder.

35

3 indicates the primary winding.

The invention is especially applicable to furnaces of such size that the stray field around the primary, between the magnet and the bath, becomes important for the 40 action of the furnace. When using a hollow magnet and placing the primary winding between the magnet and the bath the best possible magnetic action is obtained.

The drawing is only to be considered as 45 a diagram, indicating the principle of the invention; the invention may of course be carried out in different ways.

Claim.

In an electric furnace, the combination of 50 an annular furnace groove, a hollow magnet core disposed inside the furnace and a primary winding disposed between the hollow core and the furnace groove.

In testimony that I claim the foregoing 55 as my invention, I have signed my name in presence of two subscribing witnesses.

KARL ALBERT FREDRIK HIORTH.
